UNITED STATES PATENT OFFICE.

VLASTIMIL F. HEGRAT, OF CHICAGO, ILLINOIS.

KITCHEN-SINK.

1,366,910.

Specification of Letters Patent.

Patented Feb. 1, 1921.

Application filed February 19, 1920. Serial No. 359,884.

To all whom it may concern:

Be it known that I, VLASTIMIL F. HEGRAT, a citizen of the United States, residing at Chicago, in the county of Cook and State of Illinois, have invented a certain new and useful Improvement in Kitchen-Sinks, of which the following is a full, clear, concise, and exact description, reference being had to the accompanying drawings, forming a part 10 of this specification.

My invention relates to kitchen sinks and has for its object the provision of a structure of this kind in which instrumentalities are provided to increase their effectiveness.

15 In the form of my invention herein disclosed I provide a combined structure arranged in such a manner that there is a sink portion next to a shelf or drain portion. The drain portion is so arranged that a shelf 20 is provided which is slideable and which may be drawn outwardly so as to increase the shelf portion or sink structure or it may be slid back into position of non use at which time the supplemental shelf is out of the way. 25 Within the drain portion there is also provided a drawer for the accommodation of those necessary kitchen utensils which are used in connection with household operation.

30 I will describe my invention more in detail by referring to the accompanying drawings illustrating the same, in which—

Figure 1 is a perspective view of a sink structure embodying my invention;

35 Fig. 2 is a sectional view on line 2—2 of Fig. 1;

Fig. 3 is a sectional view on line 3—3 of Fig. 2; and

Fig. 4 is a front view of a modified form.

40 Referring more particularly to Fig. 1 the sink structure there shown comprises a back portion 10 together with a forwardly projecting sink portion 11, a drain or shelf section 10 also projecting forwardly of the 45 back section 10. Suitable faucets 13 and 14 may project through the back portion but these form no part of the structure of my invention. Within the shelf portion of the device there is mounted a supplemental slide 50 shelf 15 having a suitable hand hold 16 so that it may be withdrawn or pushed back into place as the case requires. The shelf portion 12 has suitable ways or guides 17 on top of which the supplemental shelf 15 55 may slide. This supplemental shelf is made of metal having the top plate 18 and the

downwardly projecting sides 19. The side portions 19 of the supplemental shelf 15 are grooved so as to form the grooves 20. Near the inner extremity of these grooves stop 60 pins 21 are provided which are mounted upon the supplemental shelf 15 within the grooves. Suitable stops 22 are provided in the side walls of the sink structure which can be mounted in position so as to firmly 65 hold and prevent complete extraction of the supplemental shelf 15. It will be noted that the groove 20 is deep enough so that these stops 22 may be inserted in place when the shelf is in position and cemented in the 70 holes provided for their reception. The shelf portion 12 is also provided with a further opening at the bottom of which there are ways or guides 23 and these support a metal drawer 24, this metal drawer 75 having the suitable hand hold 25 preferably shaped in the form of a socket as more clearly apparent from an inspection of Fig. 2.

In Fig. 4 I show a modified form of the 80 device having the back plate 10^a and having two sliding shelves 15 and two drawers 24. In other respects the structure of Fig. 4 is similar to that shown in Fig. 1.

It will thus be seen that a self-contained 85 sink structure is provided carrying the necessary instrumentalities for efficient use.

Having thus described one form of my invention what I claim as new and desire to secure by Letters Patent is.

1. A sink structure of the character described having a back wall, a sink portion extending forwardly from said back wall, an integral shelf portion immediately next to the sink portion also extending forwardly 95 from said back wall, said shelf portion having an integral depending portion, and a drawer slidably mounted within the depending portion of the aforesaid portion.

2. A sink structure of the character described having a back wall, a sink portion extending forwardly from said back wall, an integral shelf portion immediately next to the sink portion also extending forwardly from said back wall having a depending 100 apron, a drawer slidably mounted within the shelf portion aforesaid, and a shelf having a depending side flange slidably mounted within said shelf portion, said flange co-operating with guide ribs formed on said 110 apron.

3. A sink structure of the character de-

scribed having a back wall, a sink portion extending forwardly from said back wall, an integral shelf portion immediately next to the sink portion also extending forwardly 5 from said back wall, a drawer slidably mounted within the shelf portion aforesaid, a shelf having a depending side flange slidably mounted within said shelf portion, said side flange being provided with an inwardly offset portion forming a groove, and stops to prevent complete withdrawal of said shelf portion extending into said groove.

4. A sink structure of the character described having a back wall, a sink portion 15 extending forwardly from said back wall, a shelf portion immediately next to the sink portion also extending forwardly from said back wall, a drawer slidably mounted within the shelf portion aforesaid, a shelf slidably 20 mounted within said shelf portion, and stops to prevent complete withdrawal of said shelf portion, said shelf portion having grooves into which said stops project.

5. A sink structure of the character described comprising a sink portion, a fixed 25 shelf portion adjacent said sink portion, said sink portion having a depending apron extending below said shelf portion having openings therein to slidably receive a shelf 30 and drawer therein, and guides formed in-

tegral with said apron for said shelf and drawer.

6. In a sink structure, a fixed shelf portion provided with a depending apron, an inwardly extending rib cast integral with 35 said apron, a shelf slideable in said sink structure, said shelf having a depending flange at the side thereof, said slideable shelf being guided between the under face of said fixed shelf portion and said rib with the lower 40 edge of said flange in engagement with said rib.

7. In a sink structure, a fixed shelf portion provided with a depending apron, an inwardly extending rib cast integral with said 45 apron, a shelf slideable in said sink structure, said shelf having a depending flange at the side thereof, said slideable shelf being guided between the under face of said fixed shelf portion and said rib with the lower 50 edge of said flange in engagement with said rib, said flange being provided with an inwardly offset portion forming a groove and cooperating stops on said apron and flange projecting into said groove.

In witness whereof I hereunto subscribe my name this 28th day of January, A. D. 1920.

LASTIMIL F. HEGRAT.
